CAN OPENER

Alan F. Eckel, Chicago, Ill., assignor to Sears,
Roebuck and Co., Chicago, Ill.

Filed June 21, 1971, Ser. No. 155,390

Term of patent 14 years

Int. Cl. D7—04

U.S. Cl. D8—36

FIG. 1

FIG. 2

FIG. 3

FIG. 4

FIG. 1 is a front top perspective view of a can opener showing my new design; and

FIG. 2 is a rear view thereof.

FIG. 3 is a side elevation thereof as seen from the left of FIG. 1; and

FIG. 4 is a fragmentary side elevation view of the can opener with the can lid holder in a raised position.

The bottom of the design is substantially plain and unornamented.

I claim:

The ornamental design for a can opener, as shown and described.
